UNITED STATES PATENT OFFICE.

JAY G. MITCHELL, OF CLEVELAND, OHIO, ASSIGNOR TO THE NORTH ELECTRIC COMPANY, OF CLEVELAND, OHIO, A CORPORATION OF OHIO.

ELECTRIC SIGNAL-RECEIVING APPLIANCE.

1,027,351.

Specification of Letters Patent.

Patented May 21, 1912.

Application filed July 26, 1907. Serial No. 385,617.

To all whom it may concern:

Be it known that I, JAY G. MITCHELL, a citizen of the United States of America, and a resident of Cleveland, in the county of 5 Cuyahoga and State of Ohio, have invented certain new and useful Improvements in Electric Signal-Receiving Appliances, of which the following is a specification.

My invention relates to improvements in signal-receiving appliances, and more particularly to those employed in connection with combined telegraphic and telephonic systems; although my said improvements are not necessarily restricted thereto in their 15 employment. In such combined systems, a relatively sensitive signal-receiving appliance is desirable, if not necessary, but such appliance obviously must be capable of affording a sufficiently loud signal to be 20 heard under ordinary conditions, at a considerable distance from the telephone instrument. Ordinarily the signal must be distinctive and marked in order to be practical. The usual mode of transmitting such 25 signals is to impress upon the connected circuit, an alternating current which will most strongly affect the signal-receiver, but because of adverse conditions and relatively long and poorly constructed lines, I have 30 found that ordinary means are not adequate for giving the required signal. Accordingly, I have adapted the general type of telephone receiver, as the most sensitive and practical instrument for translating such alternating currents into the required signal, and have modified and improved such telephone receiver in the manner hereinafter pointed out and claimed, whereby the signal 35 therefrom is amplified, and the efficiency of the instrument is greatly improved.

Briefly stated, the preferred embodiment of my invention, comprises a telephone receiver, wherein the electro-magnet is made adjustable toward and from the vibratory 45 diaphragm. Associated with said diaphragm is a shallow sound chamber and a trumpet or mouth piece for amplifying the sound. The sound chamber is most simply and cheaply formed by means of an annular 50 member resting upon the main diaphragm of the receiver, and a perforated diaphragm carried thereby in close proximity to the former, and having a centrally mounted trumpet extending therefrom.

Further details of construction will be

more readily gathered by making reference to the accompanying sheet of drawings and the specifications explanatory thereof.

Figure I of said drawings is a view in side elevation of the preferred embodiment 60 of my invention. Fig. II is a view partially in vertical section thereof. Fig. III is a detail in section, showing the electro-magnet and adjusting means of the appliance. Fig. IV is a transverse sectional view on line 65 IV—IV, Fig. II. Fig. V is a top view of the device; and Fig. VI is a detail showing the perforated supplemental diaphragm and a portion of the associated horn or mouth piece.

Throughout each of the several figures of the drawings, I have indicated similar parts by the same character of reference.

Inasmuch as the structure follows closely upon the lines of commercial telephone receivers, extended explanation will not be necessary. In my improved device, the permanent magnet *p* mounts the soft iron pole pieces *e' e* of the electro-magnet *e* whose windings are connected with the conducting cord *c* for attachment to the exciting circuit. Between the extended poles of the electro-magnet and the limbs of the permanent magnet, is mounted a double segmented threaded member *t* secured in place 75 by means of a transverse screw *t'*. Through longitudinal openings in the member *t* extend the insulated conductors *c' c'* which unite the conducting cord with the windings of the electro-magnet. A bell-shaped cup *b*, 80 preferably formed of a relatively heavy casting, is threaded upon the member *t*, while a lock-nut *n* is disposed immediately beneath said cup, to retain the parts in their 85 positions of adjustment. These members obviously should be formed of non-magnetic metals to avoid closing the magnetic lines of force. Positioned upon the annular rim of cup *b*, is the magnetic diaphragm *d*, responsive to currents flowing in the electro-magnet *e*. Associated with said diaphragm 90 is the sound chamber, which is most readily and cheaply formed by means of an annular fiber washer or spacing member *w*, and the supplementary diaphragm *d'* superposed 95 thereon closely adjacent to diaphragm *d*. The supplementary diaphragm has its center perforated, and attached thereto is the horn or mouth piece *m*, the outer opening of which preferably is closed by means of 100

110

wire gauze m' . Securing the diaphragms together, and completing the sound chamber, is the threaded annulus r , wherein is screwed the cup b , which retains the diaphragms peripherally in close proximity, while permitting maximum vibration at their centers.

From the construction described, it will be seen that the poles of the electro-magnet 10 are adjustable toward and from the main diaphragm d , to insure the highest efficiency or response for any given current impressed upon the line. By reason of the relatively heavy castings forming the bell and annulus, the sound chamber is so mounted as to 15 augment the effect of the electro-magnet, while the trumpet or mouthpiece, not only serves to transmit the vibrations from the main diaphragm and sound chamber and give 20 direction thereto, but greatly increases the surface of the supplementary diaphragm, which is set into vibration through the medium of the air within the shallow sound chamber. In consequence, the instrument 25 described is adapted greatly to augment the sound-producing effect of currents transmitted through the windings of the electro-magnet e , and accordingly, the appliance set forth is admirably adapted for signaling 30 upon composite telephone and telegraph lines, or other electrical circuits. It may also be otherwise employed, as for example, in amplifying telephonic conversations, or wireless telegraph signals.

35 In practice, the signaling appliance is secured within the telephonic instrument by means of screws passing through the upper rim of the annulus r into a shelf v , with the protected opening of the trumpet or mouth piece registering with a corresponding opening 40 in the casing v' of the telephone instrument, yet wholly free and unimpeded in its vibrations. Serving as it does to increase the vibratory body or surface of the supplemental diaphragm and sound chamber, the 45 horn or mouth piece materially augments the volume of the signal produced, but obviously the same may be dispensed with, if desired.

50 The preferred signal is one produced by alternating currents, small in quantity, and of such frequency as will not affect relays or other telegraph instruments connected upon the line. The signal produced resembles 55 the tone of a cornet, which may be heard in a large room at a considerable distance from the telephone, and is so distinctive as to overcome ordinary sounds, such as those of telegraph instruments or passing trains, 60 for example, and thereby call the party to the telephone instrument.

While I have described the preferred construction of my improved signal-receiver and its customary employment, I do not wish to be understood as limiting the same either to such construction or use, further than is to be properly inferred from the appended claims, and

I desire to secure by Letters Patent, the following:

1. In a device of the class described, the combination with an electro-magnet, of a vibratory sound chamber comprising a main and a perforated diaphragm positioned closely adjacent to each other, a horn directly attached at the opening within the latter and supported in position freely to vibrate, a relatively massive anchorage annularly engaging the diaphragms, and means for securing the adjustment of the electro-magnet with relation to the sound chamber, substantially as set forth.

2. In an electro-magnetic receiver, the combination with permanent and electro-magnets, of a vibratory diaphragm positioned before the electro-magnet, a supplementary diaphragm, an interposed member forming a shallow sound chamber, and a horn or mouth piece directly engaging a wall of the sound chamber thus formed, substantially as set forth.

3. In a device of the class described, the combination with permanent and electro-magnets, of a vibratory diaphragm positioned before the electro-magnet, a supplementary diaphragm, having a central opening, a horn or mouth piece secured thereto at said opening, and an annular member interposed between the two diaphragms and thereby serving to form a shallow sound chamber, substantially as set forth.

4. The combination with a permanent magnet, of an associated electro-magnet, a threaded member between the poles thereof, a relatively heavy bell or cup into which the threaded member is screwed, a magnetic diaphragm, an annular spacing member, and a perforated supplemental diaphragm superposed, and resting upon the rim of the bell, an annulus securing said parts together, and a horn or mouth piece associated with the supplemental diaphragm and supported in position freely to vibrate, substantially as set forth.

Signed at Cleveland, this 22nd day of July, 115 A. D. 1907, in the presence of two subscribing witnesses.

JAY G. MITCHELL. [L. S.]
